ATTORNEY

UNITED STATES PATENT OFFICE.

GUSTAF NYHOLM, OF BROWNSVILLE, WASHINGTON.

LAYING SHINGLES.

Application filed June 28, 1924. Serial No. 722,910.

The invention is the placing of double shingles on a roof or the like with the butt of the upper shingle extending beyond the butt of the lower shingle so that the lower shingle will be protected from the weather and also so that water dripping from one shingle to another will strike the lower shingle a short distance from the butt of the shingle above it.

10 The object of the invention is to provide a shingle roof that will wear indefinitely.

Another object of the invention is to provide a means for laying shingles so that there will be a shingle foundation to the roof 15 which will be protected by other shingles at the surface.

And a further object of the invention is to provide a means for diverting the drip from one shingle on a roof to another so 20 that it will be spread over the surface of the shingles.

With these ends in view the invention embodies the placing of double shingles on the roof and the extending of the butts of the 25 upper shingles beyond the butts of the lower shingles.

Other features and advantages of the invention, will be seen from the following description of the invention taken in connection 30 with the drawing, wherein:—

The drawing illustrates a section of a roof with the shingles placed thereon.

In the drawings I have indicated the shingles by the numeral 1, the butts of the 35 upper shingles by the numeral 2, and the butts of the lower shingles by the numeral 3.

It will be observed that the first row of shingles may be laid double with the butts

flush and then an additional row placed upon them with the butts extending beyond 40 the butts of the former shingles as shown in the drawing. The next row may be placed upon the first row in the usual manner and then an additional row placed upon this row with the butts of the shingles of the additional row extending beyond the butts of the shingles of the lower row. The remaining rows may be placed in the same manner 45 until the entire roof is covered. It will be observed that it will be possible to lay the 50 shingles with more space to the weather so that it will not require many more shingles to lay the roof in this manner than in the usual manner.

It will also be observed that the shingles 55 may be held on the roof in the usual manner or may be held by continuous straps between them as indicated in dotted lines and by the numeral 4, in which case the nails would be placed through the strips between 60 the shingles.

The shingles referred to are wood cedar shingles, however, it is understood that they may be made of any suitable material.

Having thus fully described the invention, what I claim as new and desire to secure by Letters Patent, is:—

A roof comprising two rows of shingles in each course thereof, the shingles of the upper row being extended at their lower 70 edges to overlie the lower edges of the shingles of the corresponding bottom row, to protect the lower shingles from the weather and to provide a drip extension.

GUSTAF NYHOLM.
